DISPLAY DEVICE

Robert L. Mason, Pittsburgh, Pa., assignor to
James W. Critchfield, Pittsburgh, Pa.

Application October 13, 1930, Serial No. 488,446
Renewed August 22, 1933

2 Claims. (Cl. 206—72)

This invention relates to display devices, and its general object is to provide a tray for displaying merchandise on a store or shop counter and the like, as well as for the purpose of receiving change for a customer after a sale or the like.

A further object of the invention is to provide a combined merchandise display and change tray that is especially attractive so as to promote the sale of certain kinds of merchandise such as chewing gum and other package confections, yet is extremely useful for other purposes, such as receiving change, as well as advertising merchandise on display thereon.

15 Another object of the invention is to provide a device of the character set forth, that is simple in construction, inexpensive to manufacture, and efficient in operation and service.

This invention also consists in certain other 20 features of construction and in the combination and arrangement of the several parts, to be hereinafter fully described, illustrated in the accompanying drawing and specifically pointed out in the appended claims.

25 In describing my invention in detail, reference will be had to the accompanying drawing wherein like characters denote like or corresponding parts throughout the several views, and in which:

Figure 1 is a top plan view of the device which 30 forms the subject matter of the present invention.

Figure 2 is a sectional view taken approximately on line 2—2 of Figure 1, looking in the direction of the arrows.

Figure 3 is a front elevation of my device.

35 Figure 4 is a sectional view illustrating a manner of connecting a portion of the device with the base thereof.

Referring to the drawing in detail, the reference numeral 1 indicates the base of my device 40 which is preferably formed from rubber or similar resilient material or composition, and as will be noted upon inspection of Figures 1 and 2, it is relatively thin and flat, as well as being substantially rectangular in shape, with converging side 45 walls and rounded ends.

The forward end which for distinction is indicated by the reference numeral 2 is rounded to a greater degree than the rearward end so that the forward end can be readily distinguished as will 50 be apparent.

Formed with the base 1 in a manner to be disposed adjacent the side edges thereof as well as the rearward edge, and also rising from adjacent the center of the base are knobs 3 which include 55 shanks and enlarged heads as will be noted upon

inspection of Figure 4. These knobs are formed from the same material as the base, and are adapted to detachably receive lugs 4 which are formed with the body member 5 of the device, the lugs being provided with openings to accommodate the knobs as clearly shown in Figure 2 of the drawing.

The body member may be formed of sheet metal and includes an inclined top wall 6 which merges at its forward end into a forward extending front 65 wall 7. The side walls of the body member follow the shape of the side walls of the base, and the rear wall follows the shape of the rearward edge of the base as will be noted upon inspection of Figure 1.

The top wall 6 as shown is provided with elongated openings 8 and these openings are adapted to receive like shape container members 9, the latter being provided with lugs 10 which are riveted or otherwise secured to the top wall 6 by 75 suitable securing means 11 in a manner whereby these container members are disposed below the surface of the top wall and held suspended in spaced relation with respect to the base as clearly shown in Figure 2. The container members may 80 be formed from the same material as the body member, but in any event are adapted to receive package confections such as chewing gum or the like.

While advertising matter may be placed on the 85 device at any appropriate place desired, it is my intention that suitable advertising matter be disposed upon the forwardly extending front wall 7, as well as upon a space 12 primarily designed 90 for that purpose, the space being retained in a smooth condition, while the remaining portion of the base especially forwardly beyond the body member is serrated as at 13, it being apparent that the serrations will have a tendency to retain 95 change such as silver and the like and therefore prevent the latter from rolling or casually sliding from the base.

From the above description and disclosure of the drawing, it will be obvious that I have provided a combined merchandise display and change receiving device that is extremely useful for the purpose intended and will not only be attractive, but will likewise promote the sale of merchandise due to the fact that a customer upon receiving his change from a sale will naturally note 100 the device and the merchandise therein, therefore the device will call the attention of a casual observer to the merchandise.

It is thought from the foregoing description 110

that the advantages and novel features of my invention will be readily apparent.

I desire it to be understood that I may make changes in the construction and in the combination and arrangement of the several parts, provided that such changes fall within the scope of the appended claims.

What I claim is:

1. A combined merchandise display and change receiving device comprising a base, a body member detachably secured to the base and having an inclined top wall formed with openings, container members disposed below said openings, lugs formed with said container members and

15

secured to the top wall, and said container members being adapted to receive merchandise.

2. A combined merchandise display and change receiving device comprising a resilient pliable base, a body member supported upon said base, lugs formed with the body member and having openings therein, resilient pliable knobs formed with the base and received in said openings for detachably securing the body member to said base, and open top containers arranged in said body member and secured to and depending from the top of the latter. 80 85
